CLAIM

The ornamental design for a security sensor for a door or a window, as shown and described.

DESCRIPTION

FIG. 1 is a perspective view of a security sensor for a door or a window showing our new design;

FIG. 2 is a front side elevational view thereof;

FIG. 3 is a rear side elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines illustrate portions of the security sensor for a door or a window that form no part of the claimed design.

1 Claim, 3 Drawing Sheets
